UNITED STATES PATENT OFFICE.

CHARLES KENNEDY, OF PHILADELPHIA, PENNSYLVANIA.

DESIGN FOR A SLATE-PENCIL SHARPENER.

Specification forming part of Design No. 5,183, dated August 8, 1871.

To all whom it may concern:

Be it known that I, CHARLES KENNEDY, of Philadelphia, in the county of Philadelphia and State of Pennsylvania, have invented and produced a new and original Design for Slate-Pencil Sharpeners, of which the following is a specification:

My invention consists in having a casting of iron or any other hard or suitable metal, either plain or ornamented, of a convenient size and

shape, so that it can be held in the hand and readily used to reduce a slate-pencil to a fine point.

I claim as my invention—

The design for the particular shape of the pencil-sharpener, as shown.

CHAS. KENNEDY.
